UNITED STATES PATENT OFFICE.

NICHOLAS CROTSBURG, OF JANEVILLE, WISCONSIN, ASSIGNOR OF ONE-HALF TO CRAGIN BROTHERS & CHANDLER, OF CHICAGO, ILLINOIS.

PORTABLE STOVE.

SPECIFICATION forming part of Letters Patent No. 241,194, dated May 10, 1881.

Application filed November 1, 1879.

To all whom it may concern:

Be it known that I, NICHOLAS CROTSBURG, of Janesville, in the county of Rock and State of Wisconsin, have invented a certain new and useful Improvement in Oil-Stoves, of which the following is a specification.

The object I have in view is to produce a simple and cheap oil-stove, which will be economical in its use of oil and will produce complete combustion of the gases thrown off by the flames; which will be clean and convenient in use, will be constructed so that, without detracting from its usefulness for cooking purposes, it can be employed to heat flat-irons, no separate attachment for that purpose being necessary, will not require chimneys for the separate flames to promote draft and produce combustion, and will possess advantages in several other particulars, hereinafter mentioned, over the oil-stoves heretofore made; and my invention therein consists in the several novel features of construction and in the various novel combinations of the operative parts, all as more fully hereinafter explained, and pointed out by the claims.

In the accompanying drawings, forming a part hereof, Figure 1 is a perspective view of the oil-stove; Fig. 2, a top view of the same with the heating-drum thrown back; Fig. 3, a central vertical section of the oil-stove when the heating-drum is in an upright position; Fig. 4, a top view with the heating-drum removed, the horizontal diaphragm being shown in position over the cones; and Fig. 5, a separate top view of the annular base.

Like letters denote corresponding parts in all the figures.

A is the base of the stove, made annular in form, and having feet *a*, upon which it rests, such feet raising the base sufficiently to allow a free circulation of air under the same. At its top the annular base has an inwardly-projecting flange, *a'*, in which a number of slots, *b'*, are formed.

B is the oil-reservoir, of circular form, which is removably held in the annular base by a number of pins, *b*, projecting outwardly from its upper edge, and resting on the inwardly-project-

ing flange *a'* of the base. In removing the reservoir from or attaching it to the base the pins *b* pass through the slots *b'*. The reservoir being hung to the flange *a'*, a clear open space, B', is formed around the reservoir and between the same and the annular base, in which space air circulates and assists to keep the oil-reservoir cool. The slots *b'* form air-exit openings at the top of this space, so that a change of air in such space will continually take place. The reservoir B has a flange, *c*, turned up around its bottom edge, to catch any oil that may run down the sides of such reservoir, and it has a filling-opening on its top, closed by a screw-cap, *d*.

From the reservoir rise the flat wick-tubes *e*, preferably three in number, which have the usual wick-adjusting stems and wheels. Below the wick-adjusting devices each tube is provided with lateral slots *f*, located opposite each other and extending nearly the entire width of the tubes, sufficient metal only being left at the edges of the wick-tubes to give them the necessary strength. These slots cut off the heat, which would otherwise be conducted down the sides of the wick-tubes to the oil-reservoir. They allow any gases that may collect in the oil-reservoir to escape, and admit fresh air into the wick-tubes, so that the same will commingle with the oil and promote combustion. These slotted wick-tubes I intend to make the subject-matter of another application for patent, and therefore I do not claim them, broadly, in this application.

From the periphery of the annular base rise three or more posts, *g*, upon which the cone-plate C' rests, such cone-plate being hinged to one of such posts, as shown, so that the cone-plate and the heating-drum supported thereby can be thrown back to expose the parts below.

Below the cone-plate a short distance, and between the same and the oil-reservoir, is situated a circular reflector, D, of bright sheet metal. This reflector is disk-shaped or concave on its upper side, and is imperforate. It is intended to reflect or throw the heat upwardly, so as to confine the heat as much as possible to the heating-drum, and for that purpose is made imperforate and of bright metal.

The reflector D has slots, through which the wick-tubes project, and it is supported in any suitable manner.

Below the reflector is a plate or ring, h, which is soldered to the wick-tubes.

To the edge of the reflector D is secured a perforated metallic band, J, extending upwardly to the cone-plate, but not connected therewith. Through this perforated band air passes to feed the flames.

Below the plate h the center of the oil-reservoir is protected by a plate, i, raised above the reservoir by feet; or this plate i may cover the whole upper surface of the oil-reservoir.

15 The cone-plate C' has cast therewith the cones k, provided with slots coinciding in size and position with the wick-tubes that form the burners.

16 G is the heating-drum, made of sheet metal in cylindrical form, and having a number of mica-covered windows, g', in its flame-chamber G', so that the condition of the flames can be readily observed, and the stove will be useful for illuminating purposes. The sheet-metal heating-drum sets within the upwardly-projecting edge h' of the cone-plate, to which it is secured by suitable means. This upwardly-projecting edge h' has slots at intervals, which register with slots in the lower edge of the drum G, forming a number of air-openings, o, which admit air to the interior of the drum just above the cone-plate.

17 A short distance above the air-openings o the drum has a horizontal diaphragm, H, provided with holes through which the cones project. This diaphragm is notched at a number of points around its edge, producing air-openings p, Fig. 4, connecting the shallow air-chamber below this diaphragm with the flame-chamber G' above it. The diaphragm H protects the cone-plate from being heated by direct radiation from the flame-chamber, while the fresh air which enters through the openings o keeps such cone-plate from becoming highly heated, and such air, being itself heated by circulation among the cones and over the cone-plate, is discharged upwardly, through the openings p, into the flame-chamber G', where it produces the combustion of the unconsumed gases thrown off by the flames.

18 At the upper end of the flame-chamber G' and a short distance from the upper edge of the drum G is situated a head, E, which is secured at the front and rear to the walls of the drum, and at the sides is turned up so as to leave long openings l, through which the products of combustion from the flame-chamber pass upwardly. The center of the head E is provided with a single large opening of suitable shape, which is closed by a removable lid, l', Fig. 3.

19 The space below the head E, and between the same and the diaphragm H, forms the flame-chamber G', before referred to, which is a single chamber without chimneys or vertical partitions, in which the products of combustion from all the burners commingle and are

consumed, and through which they pass in a single volume.

20 The drum, above the head E and on a level with the upper side of such head, has an opening, F, on one side extending to the top of the drum, and large enough to admit the body of a flat-iron. This opening F is closed by a door (not shown) when the stove is used for baking, as will be presently explained.

21 Upon the top edge of the sheet-metal drum is secured a cast-metal ring, I, which has a shoulder adapted to receive all stove-furniture of the size for which it is made. This ring extends over the opening F; but the ring is not complete above such opening, being there severed by a slot, n, wide enough to allow the shanks of a flat-iron handle to pass through it.

22 A removable cover, C, provided with slot m, 85 extending from the edge diametrically past its center, for receiving the shanks of a flat-iron handle, is placed upon the ring I when flat-irons are to be heated. The lid l' is also placed in position so that the faces of the flat-irons 90 will not be smoked, while the heat from the flame-chamber passes through the long side openings, l, into the flat-iron chamber, and surrounds the flat-iron placed on the head E, and then passes off at the opening F. The handle 95 of the flat-iron being situated above the slotted cover C, remains comparatively cool.

23 For cooking or frying eatables or heating water, the lid l' is removed and the pot or frying-pan is placed upon the ring I, fitting closely 10 the shoulder on the same. The products of combustion rise through the center of the head E and through the openings l, and, after circulating around the bottom of the pot or frying-pan, pass off horizontally through the opening 10 F. By directing the products of combustion in this manner, instead of allowing them to pass off freely at all points around the edge of the pot or frying-pan, they are concentrated and forced more intimately into contact with the 11 cooking-vessel, and consequently give off more of their heat.

24 When a baking-oven, such as is ordinarily used with oil-stoves, is placed upon the ring I, the opening F is closed by its door, (not shown,) 11 so that the products of combustion will all pass up around the oven.

25 The heating-drum, it will be seen, is constructed to serve as a flat-iron heater in addition to its uses for cooking purposes. This peculiarity of construction does away with one of the attachments heretofore necessary to be purchased with each oil-stove, and, in addition, adapts the stove particularly for use in tailor-shops, laundries, and elsewhere where the heating of flat-irons would be the primary object.

26 What I claim as my invention is—

27 1. In an oil-stove, the heating-drum open at its upper end and having a ring adapted to receive and fit closely the stove furniture, and an opening in its side at such upper edge for the escape of the products of combustion when the top opening is closed, substantially as described.

2. In an oil-stove, the heating-drum having a horizontal head or partition near its top for supporting a flat-iron, said head or partition having openings at its periphery for permitting the upward escape of the products of combustion, in combination with an opening in the side of the drum on a level with such head, through which to slide the flat-iron, substantially as described. 50
- 5 3. In an oil-stove, the heating-drum having an open upper end adapted to receive either cooking-utensils or a cover, in combination with a perforated partition-plate secured in such drum below its open upper end, for supporting a flat-iron, and an opening in the side of the drum for the escape of the products of combustion and through which to slide the flat-iron, substantially as described. 55
- 10 4. In an oil-stove, the combination, with the heating-drum having open upper end and a side opening for flat-irons, of a head or partition plate secured therein on a level with the side opening, said head being provided with a central hole, covered by a removable lid, and with openings at its periphery, substantially as and for the purpose set forth. 60
- 15 5. In an oil-stove, the heating-drum having an open upper end adapted, as described, to receive cooking utensils, and provided with a flat-iron opening in one side, in combination with a perforated head or partition secured in such drum on a level with the side opening, and a removable slotted cover adapted to be placed on the open upper end of the drum, substantially as described. 65
- 20 6. In an oil-stove, the combination, with the heating-drum G, having open upper end, of the ring I, provided with slot n, the side opening, F, the head E, having openings l and a central hole closed by a removable cover, l', and the cover C, having slot m, substantially as described and shown. 70
- 25 7. In an oil-stove, the combination of the cone plate with the heating-drum resting thereon, and having perforations o, the diaphragm H, through which the cones project, having perforations p, and the flame-chamber G', above such diaphragm, substantially as described and shown. 75
- 30 8. In an oil-stove, the heating-drum having a shallow chamber just above the cone-plate connected with the exterior air, and a single flame-chamber extending the entire width of the drum, above the shallow air-chamber, and connected by openings with such shallow air chamber, substantially as described. 80
- 35 9. In an oil-stove, the heating-drum having a shallow air-chamber just above the cone-plate, a single flame-chamber above such air-chamber, and a chamber for holding flat-irons, above the flame-chamber, all such chambers being connected together substantially as described and shown. 85
- 40 10. In an oil-stove, the combination, with the cone-plate, supported on posts above the oil-reservoir, and the wick-tubes, of the imperforate reflector situated below the cone-plate, and the perforated band extending upwardly from the periphery of the reflector to the cone-plate, substantially as described and shown. 90
- 45 11. In an oil-stove, the combination, with the cone-plate, supported on posts above the oil-reservoir, and the wick-tubes, of the imperforate reflector D, below the cone-plate, the perforated band J, extending upwardly to the cone-plate, and the plate i, supported by feet above the oil-reservoir, substantially as described and shown. 95
- 50 12. In an oil-stove, the combination, with the base, of the removably-secured oil-reservoir B, having upturned edge e, substantially as described and shown. 100
- 55 13. In an oil-stove, the annular base A, having inwardly-projecting flange a', in combination with the reservoir D, removably hung to such flange, substantially as described and shown. 105
- 60 14. In an oil-stove, the annular base A, having inwardly-projecting flange a' and slots b', in combination with the oil-reservoir B, removably hung to such flange by pins b, and the free open space B', between the oil-reservoir and the annular base, substantially as described and shown. 110
